W. C. SPINDLER

GAME

Filed May 21, 1924

Attorney

UNITED STATES PATENT OFFICE.

WALTER C. SPINDLER, OF STEVENS POINT, WISCONSIN.

GAME.

Application filed May 21, 1924. Serial No. 714,865.

To all whom it may concern:

Be it known that I, WALTER C. SPINDLER, a citizen of the United States, residing at Stevens Point, in the county of Portage, 5 State of Wisconsin, have invented certain new and useful Improvements in Games; and I do hereby declare the following to be a full, clear, and exact description of the invention, such as will enable others 10 skilled in the art to which it appertains to make and use the same.

This invention relates to new and useful improvements in games, and particularly to games played indoors, and in imitation 15 of the corresponding games when played outdoors.

One object of the invention is to provide a game board, which is used to play a game 20 in imitation of the outdoor game of football.

Another object is to provide a game of 25 this character wherein spinners and game pieces are used, one player operating the spinners and moving certain of the game pieces, while the other player moves the other game pieces.

Another object is to provide a device of 30 this character which includes a game piece used for marking the position of a football team, while other game pieces mark the advances or retreats of the teams and the position of the ball, at the beginning of each play.

Other objects and advantages will be apparent from the following description when 35 taken in connection with the accompanying drawing.

In the drawing:

Figure 1 is a plan view of the game 40 board.

Figure 2 is a plan view of the spinners.

Figure 3 is a perspective view of one 45 of the game pieces.

Referring particularly to the accompanying drawing, 10 represents a game board which has a plurality of transverse parallel lines 11 thereon indicating single yards, and five yard positions along the football field. Formed in the center of each of the 50 transverse lines is a socket 12, which is adapted to receive the game piece 13. At

each end of the line is formed a similar socket 14 for the reception of a game piece 13. The game-piece which is placed in the sockets 12 represents the team at play, while 55 the pieces which are placed in the sockets 14 represent the yards of gain or loss, and the position of the ball, when in play.

On the board 15 are formed three dials 16, 17, and 18, and pivoted centrally in 60 these dials are the indicating hands 19, 20, and 21, respectively, for traversing said dials. The dial 16 is marked with different plays, in the game, while the dial 18 is marked to indicate the yard lines at which 65 the ball is put into play. The central dial 17 has a series of alternate 6's and 7's, for ascertaining the point scored with or without goal kicks.

In playing the game, one player moves 70 the piece from one socket to another, along the central line of sockets 12, and also spins the hands of the dials, while the other player moves a pair of pieces in the sockets at the outer ends of the transverse lines 11, 75 to indicate the position of the ball, and the yards gained or lost. The gamepiece in the central sockets is used alternately by the two players, to represent the teams, while each player has a pair of pieces for movement from socket to socket, along the ends of the lines.

What is claimed is:

A game device including a board having 80 a football field marked thereon, sockets at 85 the opposite ends of each transverse line of the field, a socket at the intermediate portion of each line, game pieces for disposition in said sockets, and spinners for ascertaining the positions and movements of 90 the pieces of the sockets of the terminal sockets, and spinners for ascertaining respectively the position of the piece of the intermediate sockets and the scores of the 95 plays.

In testimony whereof, I affix my signature, in the presence of two witnesses.

WALTER C. SPINDLER.

Witnesses:
